(57) **CLAIM**

The ornamental design for packaging for wipes substantially as shown and described.

DESCRIPTION

FIG. 1 is a top, front, left perspective view of packaging for wipes.

FIG. 2 is a left side elevation view thereof.

FIG. 3 is a right side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a top, front, left perspective view of the packaging for wipes of FIG. 1 in an open position.

FIG. 9 is a left side elevation view thereof.

FIG. 10 is a right side elevation view thereof.

FIG. 11 is a front elevation view thereof.

FIG. 12 is a rear elevation view thereof.

FIG. 13 is a top plan view thereof; and,

FIG. 14 is a bottom plan view thereof.

(Continued)

The broken lines are shown for the purpose of illustrating parts of the article that form no part of the claimed design.

1 Claim, 10 Drawing Sheets
